United States Patent Office

Des. 217,145

Patented Apr. 14, 1970

217,145

BENCH

Orville B. Solie, Rockford, Ill., assignor to Kroehler Mfg.
Co., Naperville, Ill., a corporation of Delaware

Filed Oct. 17, 1968, Ser. No. 14,041

Term of patent 14 years

Int. Cl. D6—01

U.S. Cl. D15—11

FIG. 1

FIG. 2

FIG. 3

FIG. 1 is a front perspective view of a bench showing my new design;

FIG. 2 is a side elevational view of one of two identical sides; and

FIG. 3 is an end elevational view taken from the right in FIG. 1.

I claim:

The ornamental design for a bench, as shown and described.
